UNITED STATES PATENT OFFICE.

CHARLES J. DIEGES, OF NEW YORK, N. Y.

DESIGN FOR A CUFF-BUTTON.

54,535.

Specification for Design.

Patented Mar. 2, 1920.

Application filed May 2, 1919. Serial No. 294,337. Term of patent 7 years.

To all whom it may concern:

Be it known that I, CHARLES J. DIEGES, a citizen of the United States, residing in the borough of Manhattan, city and county of New York, have invented a new, original, and ornamental Design for Cuff-Buttons, of which the following is a specification, reference being had to the accompanying drawing, forming a part thereof.

The figure is a plan view upon an enlarged

scale of a cuff button, showing my new design.

I claim,

The ornamental design for a cuff button, as shown.

CHARLES J. DIEGES.
